UNITED STATES PATENT OFFICE

JAMES F. MCINTIRE, OF DETROIT, MICHIGAN, ASSIGNOR TO UNITED STATES RADIATOR CORPORATION, OF DETROIT, MICHIGAN, A CORPORATION OF NEW YORK

METHOD OF MAKING RADIATORS

Application filed March 12, 1932. Serial No. 598,355.

This invention relates generally to the manufacture of radiators and consists of certain novel features of construction, combinations and arrangements of parts, that will be hereinafter more fully described and particularly pointed out in the appended claims.

In the accompanying drawings:

Figure 1 is a top plan view of the means embodying my invention for making the 10 radiator.

Figure 2 is a fragmentary side elevation of the construction illustrated in Figure 1.

Figure 3 is a section on the line 3—3 of Figure 1.

15 Figure 4 is a section taken substantially on the line 4—4 of Figure 3.

Figure 5 is a perspective view of the radiator and showing parts broken away and in section.

20 Figure 6 is a section on the line 6—6 of Figure 5.

Figure 7 is a detail perspective view of one of the header slabs.

25 Figure 8 is a detail perspective view of one of the intermediate slabs.

Figure 9 is a perspective view of the inner core.

Figure 10 is a sectional view taken on the line 10—10 of Figure 3.

30 Figure 11 is a sectional view taken on the line 11—11 of Figure 3.

Figure 12 is a fragmentary elevation of a slightly modified core structure.

35 Figure 13 is a fragmentary plan view of the radiator.

Figure 14 is a detail perspective view of one of the end slabs.

Referring now to the drawings, A is a radiator embodying my invention having end 40 walls 1 and 2 respectively, side walls 3 and 4 respectively extending between the outer edges of said end walls, headers 5 and 6 respectively upon the inner sides of the end walls, a steam or water-way 7 extending be-

45 tween the side walls 3 and 4 in substantially parallel relation thereto and terminally connected to the headers 5 and 6, parallel fins 8 and 9 respectively projecting laterally from opposite sides of the water-way 7 and headers

50 5 and 6 and connected to the side walls 3 and

4, and partitions 10 and 11 respectively between the fins 8 substantially midway between opposite sides of the water-way 7 and the side walls 3 and 4. As shown, the side walls 3 and 4 are thinner than the end walls 1 and 2 and have slots 13 and 14 respectively extending longitudinally thereof at points substantially midway between their upper and lower edges. Likewise the partitions 10 and 11 are provided with slots 15 and 16 respectively in substantially horizontal alignment with the slots 13 and 14 in the side walls 3 and 4. The headers 5 and 6 are substantially rectangular in shape and have threaded openings 17 and 18 respectively for the reception of suitable piping (not shown). The water-way 7 is centered relative to the side walls 3 and 4 and opens into the headers 5 and 6. Preferably the top and bottom walls 19 and 20 respectively of the water-way 7 are 55 Y-shape in cross section while the opposite side walls 21 and 22 thereof are parallel and extend between the furcations of the Y's. The fins 8 and 9 respectively are relatively thin and are preferably closely spaced in parallel relation to the end walls 1 and 2. 60

In the present instance the radiator described above is formed by three dry sand cores B, C and D respectively. As shown, the core B is solid throughout and preferably 65 comprises a pair of header portions 24 and 25 respectively and an intermediate web portion 26. Preferably the header portions 24 and 25 are substantially rectangular in shape and have cylindrical prints 27 and 28 respectively projecting upwardly from their upper ends and horizontally from their outer faces. The web 26 is relatively thin and merges into the inner walls of the headers at the centers thereof. The longitudinal edges 29 and 30 respectively of this web are 70 substantially V-shape in cross section and are substantially flush with the upper and lower ends of the headers 24 and 25, while the sides 31 and 32 respectively of the web are parallel 75 and merge into the sides of the V's. Suitable passages 32 are provided in the core B for the escape of the core gases. 80

The cores C and D are complementary to 85 each other and form a casing for the core B. 90

The cores C and D are complementary to 95 each other and form a casing for the core B. 100

Preferably the cores C and D are sectional in construction and each comprises a pair of end slabs or sections 33, two series E and F respectively of header slabs or sections 34, 5 and a series of intermediate slabs or sections 35. The end slabs 33 are provided in their inner faces at their inner upright edges with substantially rectangular recesses 36 corresponding in shape to the end walls 1 and 2 respectively of the radiator, and have semi-circular openings 37 in their inner edges opening into said recesses 36 and adapted to receive the prints 38. The header slabs 34 have parallel sides 40 and 41 respectively 15 and are provided in the sides 40 thereof with recesses 42 corresponding in area to the fins 9. Webs 40' corresponding in area to the cross sectional area of the slots 13 and 14 are provided at the outer edges 43 of the recesses 42. 20 In addition the slabs 34 are provided along the outer edges 43 of the recesses 42 upon opposite sides of the webs 40' with slots or openings 44 and 44' corresponding in area to the cross sectional area of the side walls 25 3 and 4, and are provided in their upright edges 45 with openings 46 that communicate with the recesses 36 and receive the header portions 24 and 25 respectively of the core B. The intermediate slabs 35 have parallel 30 sides 47 and 48 respectively and are provided in the sides 47 thereof with recesses 49 that correspond in area to the fins 8; webs 50 corresponding in area to the cross section of the slots 13 and 14 are provided at the outer 35 edges 51 of the recesses, while webs 52 corresponding in area to the cross section of the slots 15 and 16 project laterally from the bases of the recesses 49 in horizontal alignment with webs 50. In addition these slabs 40 35 are provided along the rear edges 51 of the recesses 49 at opposite sides of the webs 50 with slots or openings 53 and 54 respectively corresponding in area to the cross section of the side walls 3 and 4. The slabs 45 35 also have slots or openings 55 and 56 respectively extending from opposite ends of the ribs 52 and corresponding in area to the cross section of the partitions 10 and 11 and are provided in their inner upright edges 57 50 with openings 58 corresponding in shape to and adapted to receive the sides of the core B.

At this point it will be noted that the inner upright edges 45 of the slabs 34 are straight both above and below the openings 46 and 55 the inner upright edges 57 of the slabs 35 below the openings 58 are straight like the edges 45 but are irregular above said openings 58. As shown, the slabs 35 are provided above the openings 58 with short 60 straight upright edges 60 and are provided at the upper ends of these straight edges with rearwardly curved edges 61. Preferably the straight edges 60 of certain of the slabs 35 are in alignment with the straight edges 57, while the straight edges 60 of the

remaining slabs 35 are offset inwardly relative to the straight edges 57 so that when the slabs 35 are arranged as illustrated in Figure 1, the straight edges 60 form a staggered throat or prong gate 65 permitting the molten metal to flow substantially uniformly over opposite sides 31 and 32 respectively of the core B.

In use the slabs 33, 34 and 35 respectively of the core C are assembled and clamped in a suitable rack such as 70 and the slabs 33, 34 and 35 respectively of the core D are assembled and clamped in another rack such as 71. The core B is then placed on the core C and anchored by suitable chaplets (not shown) 75 whereupon the core D and rack 71 are as a unit placed upon the assembled cores B and C and rack 70. Any suitable means such as the separate clamps 73 may be used to clamp the racks 70 and 71 together to retain the cores 80 33, 34 and 35 respectively in assembled position. When the molten metal is poured into the gate 65 it will flow substantially uniformly upon opposite sides of the core B to form the water-way, thence laterally outwardly 85 in the recesses 46 and 49 to form the fins 8 and 9, thence to the openings 44, 53, 54 and 56 respectively to form the side walls 3 and 4 and partitions 10 and 11. After flowing 90 through opposite ends of the gate 65 the metal will flow about the header portions 24 and 25 and prints 28 and 29 and will thereby form the headers 5 and 6 and fins 9.

Thus from the foregoing it will be apparent that I have provided an extremely simple 100 and inexpensive method of manufacturing radiators. It is decidedly less involved than the usual molding processes wherein flasks and green sand are employed. In fact, my method avoids the usual molding operations 105 and eliminates entirely the use of metal flasks, the necessity of making green sand molds, the contact of molten metal with improperly conditioned green sand, and the consequent sand 110 tempering together with the loss of green sand. My method is performed in the core room and may be very expeditiously carried out, especially as only three dry sand cores 115 are used in the formation of the radiator. The racks are preferably made of metal and may be provided with removable liners if desired. With my method the molten metal is fed first around the core B to form the steam or water-way of the radiator where 120 the pressure when the radiator is in use is the greatest. Consequently my method insures a sound casting which will stand the required pressure. The formation of the fins is secondary and is accomplished after the preliminary casting aforesaid is formed. A defect in the steam or water-way would be a defective casting but a defect in the fins or side wall structure is not so important. However, my method provides for uniformity of 125 flow of metal so that the fin spaces 42 and 130

49 in the cores are feeders to the side wall spaces 44, 53 and 54 respectively in the cores. As a result the side walls 3 and 4 are uniform in thickness. In this connection it will be 115 noted that the slots or openings 13 and 14, 15 and 16 respectively in the side walls and partitions facilitate the removal of core gas and avoid the use of green sand for that operation.

10 Should an extra long radiator be desired the same method described herein would be employed except that I would use two center cores 80 and 81 respectively constructed and arranged as illustrated in Figure 12. As 15 shown, these cores are provided with overlapping end portions 82 and 83 respectively and have suitable passages 84 and 85 therein for the escape of core gas. Preferably these end portions have vertical cylindrical prints 86 and 87 through which the passages 84 and 85 also extend. When formed the end portions 88 and 89 respectively of the radiator may be tapped and the metal therebetween may be readily removed so that the passages 90 and 91 respectively therein will be in direct communication.

While it is believed that from the foregoing description the nature and advantages of the invention will be readily apparent, I 30 desire to have it understood that I do not limit myself to what is herein shown and described and that such changes may be resorted to when desired as fall within the scope of what is claimed.

35 What I claim as my invention is:

1. A mold for forming a radiator having end and side walls, headers upon the end walls, a fluidway extending between said headers, partitions upon opposite sides of 40 said fluidway, fins projecting laterally from opposite sides of the fluidway to said partitions, fins projecting laterally from the partitions to the side walls, and fins projecting laterally from the headers to said side 45 walls, comprising a longitudinally extending dry sand core having a relatively thin elongated body for forming the fluidway and having enlargements at opposite ends thereof for forming the headers, and two complementary dry sand cores forming a casing 50 for the first mentioned core, the complementary cores having sections in the form of slabs arranged side by side in rows, the end slabs of said rows having abutting upright 55 inner edges and being provided in their inner faces at their inner upright edges with recesses into which metal may flow to form the end walls of the radiator, the slabs next to the end slabs in said rows having openings 60 receiving the enlargements of the first mentioned core and having abutting upright inner edges above and below said openings, said last mentioned slabs having recesses into which molten metal may flow to form the 65 last mentioned fins, the bases of the recesses

just mentioned being provided at their outer upright edges with slots into which metal may flow to form portions of the side walls of the radiator, and the slabs intermediate the second mentioned slabs having openings 70 receiving the intermediate web portion of the first mentioned core and having abutting upright inner edges below said openings, the third mentioned slabs having recesses therein into which metal may flow to 75 form the first and second mentioned fins, the bases of the last mentioned recesses being provided at their outer upright edges in alignment with the slots in the second mentioned slabs with slots into which metal 80 may flow to form other portions of the side walls of the radiator and provided with slots into which metal may flow to form the partitions, the upright inner edges of the third mentioned slabs being alternately offset 85 above the openings therein relative to the abutting straight edges thereof below said openings and forming a staggered prong gate permitting molten metal poured therein to flow substantially uniformly over opposite sides of the web of the first mentioned core.

2. A mold for forming a radiator having side walls, headers between said side walls at opposite ends thereof, a fluidway extending between said headers, partitions upon opposite sides of said fluidway, fins projecting laterally from opposite sides of the fluidway to said partitions, and fins projecting laterally from the partitions to the 100 side walls, comprising a longitudinally extending dry sand core having a relatively thin elongated body for forming the fluidway and having enlargements at opposite ends thereof for forming the headers, and 105 two complementary dry sand cores forming a casing for the first mentioned core, the complementary cores having sections in the form of slabs arranged side by side in rows, said slabs having aligned slots into which metal may flow to form the side walls of the radiator and having aligned slots into which metal may flow to form the partitions, the slabs at the ends of said rows having openings receiving the enlargements of the first 110 mentioned core, and having abutting upright inner edges above and below said openings, the slabs intermediate the slabs just mentioned having openings receiving the intermediate web portion of the first mentioned 115 core and having abutting upright inner edges below said openings, said last mentioned slabs having recesses therein into which metal may flow to form the first and second mentioned fins, the upright inner edges of the last mentioned slabs being alternately offset above 120 the openings therein relative to the abutting edges thereof below said openings and forming a staggered prong gate permitting molten metal poured therein to flow substantial- 125 130

6. A mold for forming a radiator having end and side walls, headers upon the end walls provided with fluid inlets and outlets, a fluidway extending between said headers, partitions upon opposite sides of said fluidway, fins projecting laterally from opposite sides of the fluidway to said partitions, fins projecting laterally from the partitions to the side walls, and fins projecting laterally from the headers to said side walls, comprising a longitudinally extending dry sand core having a relatively thin elongated body for forming the fluidway and having enlargements at opposite ends thereof for forming the headers, said enlargements being provided with projections for forming the fluid inlets and outlets for the headers, and two complementary dry sand cores forming a casing for the first mentioned core, the complementary cores having sections in the form of slabs arranged side by side in rows, the end slabs of said rows having abutting upright inner edges and being provided in their inner faces at their inner upright edges with recesses into which metal may flow to form the end walls of the radiator, said end slabs having openings receiving certain of said projections, the slabs next to the end slabs in said rows having openings receiving the enlargements of the first mentioned core and having abutting upright inner edges above and below said openings, certain of the second mentioned slabs having openings receiving the other of said projections, said second mentioned slabs also having recesses into which molten metal may flow to form the last mentioned fins, the slabs intermediate the second mentioned slabs having openings receiving the intermediate web portion of the first mentioned core and having abutting upright inner edges below said openings, the third mentioned slabs having recesses therein into which metal may flow to form the first and second mentioned fins, said second and third mentioned slabs having aligned slots therein into which metal may flow to form the side walls of the radiator, the third mentioned slabs having aligned slots there into which metal may flow to form the partitions, the upright edges of the third mentioned slabs being spaced apart above the openings therein and forming a gate for the reception of molten metal.

7. A mold for forming a radiator having
55 end and side walls, headers upon the end
headers, a fluidway extending between said
headers, partitions upon opposite sides of
said fluidway, fins projecting laterally from
opposite sides of the fluidway to said parti-
tions, fins projecting laterally from the par-
60 titions to the side walls, and fins projecting
laterally from the headers to said side walls,
comprising a longitudinally extending dry
sand core having a relatively thin elongated
body for forming the fluidway and having
65 enlargements at opposite ends thereof for

forming the headers, and two complementary dry sand cores forming a casing for the first mentioned core, the complementary cores having sections in the form of slabs arranged side by side in rows, the end slabs of said rows having abutting upright inner edges and being provided in their inner faces at their inner upright edges with recesses into which metal may flow to form the end walls of the radiator, the slabs next to the end slabs in said rows having openings receiving the enlargements of the first mentioned core and having abutting upright inner edges above and below said openings, said last mentioned slabs having recesses into which molten metal may flow to form the last mentioned fins, the bases of the recesses just mentioned being provided at their outer upright edges with slots into which metal may flow to form portions of the side walls of the radiator, and the slabs intermediate the second mentioned slabs having openings receiving the intermediate web portion of the first mentioned core and having abutting upright inner edges below said openings, the third mentioned slabs having recesses therein into which metal may flow to form the first and second mentioned fins, the bases of the last mentioned recesses being provided at their outer upright edges in alignment with the slots in the second mentioned slabs with slots into which metal may flow to form other portions of the side walls of the radiator and provided with slots into which metal may flow to form the partitions, the upright inner edges of the third mentioned slabs above the openings therein being spaced apart and forming a gate for the reception of molten metal.

8. A mold for forming a radiator having
end and side walls, headers upon the end
walls, a fluidway extending between said
headers, and partitions upon opposite sides
of said fluidway, comprising a longitudinally
extending dry sand core having a relatively
thin elongated body for forming the fluid-
way and having enlargements at opposite
ends thereof for forming the headers, and
two complementary dry sand cores forming
a casing for the first mentioned core, the
complementary cores having sections in the
form of slabs arranged side by side in rows,
the end slabs of said rows having abutting
upright inner edges and being provided in
their inner faces at their inner upright edges
with recesses into which metal may flow to
form the end walls of the radiator, the slabs
next to the end slabs in said rows having
openings receiving the enlargements of the
first mentioned core and having abutting up-
right inner edges above and below said open-
ings, the slabs intermediate the second men-
tioned slabs having openings receiving the
intermediate web portion of the first men-
tioned core and having abutting upright in-
ner edges below said openings, the second and

third mentioned slabs having aligned slots therein into which metal may flow to form the side walls of the radiator, the third mentioned slabs having aligned slots therein into which metal may flow to form the partitions, the upright inner edges of the third mentioned slabs above the openings therein being spaced apart and forming a gate for the reception of molten metal.

- 10 In testimony whereof I affix my signature.
